UNITED STATES PATENT OFFICE

137,163

DESIGN FOR A BRILLIANT CUT DIAMOND OR SIMILAR ARTICLE

Edward Goldstein, Brookline, Mass.

Application May 5, 1943, Serial No. 110,125

Term of patent 14 years

To all whom it may concern:

Be it known that I, Edward Goldstein, a citizen of the United States of America, residing at Brookline, in the county of Norfolk and Commonwealth of Massachusetts, have invented a new, original, and ornamental Design for a Brilliant Cut Diamond or Similar Article, of which the following is a specification, reference being had to the accompanying drawing, forming a part thereof.

Fig. 1 is a plan view of a brilliant cut diamond embodying my invention; and

Fig. 2 is a side elevation thereof.

I claim:

The ornamental design for a brilliant cut diamond or similar article, substantially as shown.

EDWARD GOLDSTEIN.
